UNITED STATES PATENT OFFICE.

THOMAS J. DIXON, OF MADISON, WISCONSIN.

TUBE-EXPANDER.

1,269,688.

Specification of Letters Patent. Patented June 18, 1918.

Application filed April 2, 1917. Serial No. 159,158.

To all whom it may concern:

Be it known that I, THOMAS J. DIXON, residing at Madison, in the county of Dane and State of Wisconsin, have invented a new and Improved Tube-Expander, of which the following is a specification.

My invention has reference to improvements in tube expanders and it primarily has for its object to provide a tool or implement of the character stated in which the cooperating parts are so designed and have such adjustment whereby the said tool or implement is rendered capable of expanding boiler tubes of different diameters of standard sizes under all the varying conditions that come up when putting in the tubes, particularly when the tube holes in the flue sheet vary in size, which frequently occurs when retubing boilers, and also when the tubes vary in their lengths outside of the flue sheet.

Again, my invention has for its purpose to provide a tube expander that includes in its make-up, an improved arrangement of parts that render the mandrel self-feeding, that is drawing it forwardly into the tube as it is rotated, and thereby obviate the necessity of driving the mandrel longitudinally for contacting with the expanding rollers.

Another and essential feature of my invention lies in an improved means for holding the expanding rollers from falling out of place and to provide for conveniently removing them singly from the body or shell.

In its more complete nature, my invention embodies certain improved means for holding the expanding rollers in their operative condition, and at the same time avoid the use of outside shoulders or stops for limiting the radial adjustment or set of the said rollers, and thereby provide a greater radius of expansion, than has, so far as I know, been possible in tube expanders of the type to which my improved expander relates.

With other objects in view that will appear in the following description of the construction of my tube expander, this invention, in its more subordinate features, consists in the peculiar combination and novel arrangement of the parts hereinafter ex-

plained, specifically pointed out in the appended claims and illustrated in the accompanying drawings, in which:

Figure 1 is a perspective view of my improved tube expander and it illustrates the preferred form.

Fig. 2 is a vertical longitudinal section thereof, and showing it as operatively applied in a tube, the rollers being indicated at a relatively minimum expanding position. 60

Fig. 3 is a side elevation of the expander, in a tube, one of the rollers being indicated at a relatively maximum expanding position in dotted lines.

Fig. 4 is a diagrammatic face view of the front end of my expander, the flue sheet, the correlation of the said front end with the adjacent tubes being also shown.

Fig. 5 is a transverse section of my improved tube expander taken on the line 5—5 70 on Fig. 2.

Fig. 6 is a similar view, on the line 6—6 on Fig. 2.

Fig. 7 is a perspective view of one of the expanding rollers, the holder therefor, and the resilient support for the holder.

Fig. 8 is a detail view of the mandrel or expanding pin.

Fig. 9 is a perspective view of the spring clamp device used when removing the rollers from the holder or body member. 80

Fig. 10 is a detail view that illustrates the manner that the spring clamp device shown in Fig. 9 is used.

Fig. 11 is a detail longitudinal section of a modified form of the body and collar, hereininafter mentioned.

Fig. 12 illustrates an arrangement of parts whereby the guard members are held in place by the bearing boxes. 90

Fig. 13 is a detail of a construction of the bearing ring segments.

Fig. 14 is a detail view of the mandrel used to expand tubes larger than can be expanded with the usual mandrel. 95

Fig. 15 is a detail plan of the expander shell and which clearly illustrates the slot-way for the expanding rollers and bearing boxes.

Fig. 16 is a detail plan of the roller and 100

spring clip held bearing boxes that coöperate therewith.

Fig. 17 is a diagrammatic plan illustrating the coöperative relation of the roller and 5 the mandrel.

Fig. 18 is a diagrammatic elevation of the parts shown in Fig. 17.

Fig. 19 is an end elevation illustrating the manner in which the spring clips are 10 turned out of engagement with the expander shell.

In the drawings, I have shown an improved construction of tube expander whose parts are coöperatively designed for expanding 15 five normal standard sizes of tubes, or any intermediate size that may come within the limits of the said five sizes.

1 designates a tapered mandrel which, when forced in between the expanding rollers, 20 2, serves to radially project the said rollers 2 to their tube expanding position.

The outer end of the mandrel is shaped for receiving the crank or other driving means.

25 3 designates a tubular body or shell that has a plurality, (preferably three) radially straight slots 4 into which the expanding rollers 2 are received as will presently be fully explained.

30 Each roller 2 has a center bearing 5 at each end and the said bearings 5 fit into corresponding bearing boxes 6—6, each of which has a socket 7 (see Fig. 2). The boxes 6—6 are freely slideable in the slots 4, 35 and each box 6 has grooves 8—8 in the opposite sides thereof for receiving and clamping the edges 90—90 of U shaped spring clamps 91—91 formed on a flat spring holder 9 that extends lengthwise of

40 the slots 4 and the rollers 2 contained therein, and each of the holders 9 has a longitudinal slot 92 through which the mandrel engaging faces of the rollers 2 are projected, as is best shown in Figs. 5 and 7, by reference 45 to which it will be also seen the spring holder 9 has its opposite ends projected beyond the slots 4 in the shell and seat in longitudinal grooves 10—10 on the internal face of the said shell or tubular body 3.

50 By providing a holding means for the rollers 2, as shown and described, the said rollers are at all times, by the resilient tension of the holders 9, drawn inwardly to their normal position, see Fig. 2, and are 55 held from falling out by reason of the socketed bearing 6 being held from falling out of the slots 4 by the clamps 90—91, it being apparent from the drawings that as the mandrel is rotated and feeds forwardly

60 in the manner presently explained, to expand the rollers 2, the spring holders 9 flatten with the ends sliding outwardly in their respective grooves 10 in the body 3.

At this point, it should be mentioned,

that by reason of mounting the expanding 65 rollers 2, as stated and shown, no external shoulders or stops, such as are usually necessary in the general run of expanders, are required, and as the rollers are attached to resilient holding elements secured to the 70 inner side of the body and which tend to normally pull the rollers inwardly, as pressure is applied to expand the rollers, the said rollers can be projected to a greater radius than is possible in expanders having 75 external shoulders or kindred devices for limiting the outward movement of the said rollers.

Another advantage in the use of the spring holder for the roller, as stated, is 80 that it retains the end socket bearings on the rollers, when for any reason the rollers must be taken out of the body of the tool, thereby at all times keeping the rollers from falling out, and also at all times keep the 85 rollers against the mandrel when the latter is in the body of the tool.

As before stated, my tube expander is of that type in which the mandrel, as it is rotated, is automatically fed forwardly it being understood that the shell or holder and the expanding rollers are held in a fixed relation with respect to the tube, that is from moving forwardly along the tube, by reason of the guard member 12, presently again 95 referred to, bearing against the outside of the flue sheet, as is clearly shown in Fig. 2.

In my construction of expander, when it is operatively applied, there is a tendency of the holder or shell and the rollers to feed 100 forwardly, such action being produced by the manner in which the rollers 2—2 are mounted on the holder.

Referring now more particularly to Figs. 15, 16, 17 and 18 of the drawings, it will be 105 noticed that the slots 4 in the holder have their central portions arranged in a plane diagonal with respect to the longitudinal plane of the holder and the opposite ends of the said slots 4 in which the boxes 6—6 110 work, are offset but in the longitudinal plane of the holder, it being understood from the drawings, that the faces of the boxes 6—6 that engage the ends of the rollers 2 are beveled and have the sockets 7—7 115 arranged for receiving the center bearings 5—5 that project in the longitudinal axis of the rollers.

By mounting the rollers 2, as stated and shown, the said rollers, as they are forced 120 out against the tube, engage the tube in such manner, that there is a constant tendency for the rollers to creep forwardly within the tube, and since any forward movement of the rollers 2 and the holder 3 125 is prevented by the guard 12 holding back the holder and the rollers, and further since the positioning of the said rollers 2 pro-

vides for the said rollers engaging the mandrel at one point only—at the transverse center of the roller as indicated by $a-a$ on Figs. 17 and 18, it follows that a screw feed 5 action from the rollers to the mandrel is thereby produced that tends to constantly force the mandrel forwardly, see arrow y , Figs. 17 and 18, and thus provide for the self-feeding operation for the mandrel, as 10 before stated.

11 designates a collar and 12 the guard member before referred to and both are removably mounted on the outer end of the body 3, the said outer end of the body being 15 tapered as at 30 to hold the collar from passing over such end as it is slipped onto the body and slid along such body in the direction of the arrow z on Fig. 2.

Guard 12, which is likewise slid endwise 20 onto the body 3, includes finger-like portions 13 that project over the end of the tube 14 to be expanded and form a bearing for engaging the flue sheet 15.

To provide for a smooth and easy rotation of the body 3 with its expanding elements, a plurality of conical roller bearings 19 are carried on the inner face of the collar 18 that engage the outer end of the guard 12.

Rollers 19 may be applied to the collar 11 30 in any suitable manner.

In the drawings, I have shown the collar formed with an annular groove 11^a in which the rollers are received, and for holding the rollers in proper operative position, they 35 have headed shanks 19^a which, when fitting the rollers in place, are slipped through a correspondingly shaped slot 11^b in the rim portion 11^c of the collar, see Figs. 2 and 6, and to hold the rollers to the desired positions spacing ring segments 80 are provided 40 that fit into operative engagement with the collar and the rollers, as shown.

To secure the collar 11 in operative position on the body 3, suitable spring clip devices are mounted thereon, as is best shown 45 in Figs. 1, 2 and 19, from which it will be seen the spring clips 65 secured to the collar have their outer ends formed with snap clips 66—66 that engage the outer face of the collar 50 and a clip 67 that interlocks with the outer tapered end of the body 3, the said end having a cam groove 68 so arranged that in turning the collar and the holder 3 in opposite direction, as indicated by the arrows in 55 Fig. 19, the locking clip members 67 unlocks from the body 3; and thereby permits pulling the collar 11 off.

22 designates a spring clamp, the construction of which is best shown in Figs. 9 60 and 10. This clamp is usually carried on the larger ends of the mandrel and is used only when it is desired to remove the rollers 2, which is done by spreading the clamp with its edges 23 to straddle over the adjacent

edges of a pair of slots 4 to bear against 65 the rollers that project up through the said slots. When two rollers are thus clamped at their outwardly extended positions and the mandrel is drawn back out of the body 3, the other roller can be readily dropped 70 back into the core of the said body 3 and slipped endwise out of the said body; it being understood that the other rollers 2 may be likewise removed.

My expander can be actuated by hand or 75 by power mechanism and it may be made to expand any size tube from 1 $\frac{1}{4}$ inches to and including 2 $\frac{1}{2}$ inch tubes.

While I prefer to operate my expander under a self-feeding action, I desire it understood that it may be operated by driving the mandrel by hand, if desired, instead of making the mandrel a long continuously tapered one, it may be made of two members tapered as shown in Figs. 8 and 14.

From the foregoing description taken in connection with the drawings, the complete construction, the manner of using and the advantage of my tube expander will be readily apparent to those skilled in the art to which 90 this invention relates.

Among other advantages, it should be stated, that the construction of my expander is such that the rollers can be expanded or set out to a greater radius than is possible 95 with other expanders now in use of corresponding size, enabling me, with my expander to expand tubes of all standard sizes, which is accomplished by having a larger bore in the center of the body 3 that admits 100 of using a mandrel member of greater variations in diameter between the small end and the large end, thereby making it possible to expand a greater variety of sizes or diameters of tubes than can, so far as I know, be done 105 by any other expander.

In my construction of expander, frictional contact of the operating parts is reduced to the minimum, this being provided for by the mounting of the expanding rollers so that they do not contact with the sides of the slots in which they work and forming them with center and socket bearings.

Again, in my construction, on account of the socket bearing members fitting closely in the body slots, it is impossible for the body of the holder to shift its position when in use.

The socket bearings do not touch inside the tube at any stage of the operation and as the socket bearings fit closely in the slots, they hold the body of the expander on center at all times.

While I prefer to make the collar 11 as a separate member, it may be formed integral with the body 3, as shown in Fig. 11, which also shows a means for holding the guard member up against the collar.

By referring to Figs. 2, 7 and 12, it will be

seen that the outermost members 6 have projecting lips 21 so arranged that the guard 12, when slipped onto the body 3, engages the said lips and rocks and depresses the said members 6 at that end, to allow the guard to slip over the lip 21, it being understood that when the guard has passed the lip 21, the spring tension on the roller holder 9 forces the lip up into the position shown in dotted lines on Fig. 12, which then serves as a stop for holding the guard 12 up to the collar.

I desire it understood, however, that I do not limit myself to the use of lips 21 on the members 6 for holding the guard up to the collar, since any other means may be employed for holding the guard and the collar in close connection.

While the general arrangement of the parts shown and described present a practical and efficient construction of my improved tube expander, I do not limit myself to the exact details of construction and arrangement of the parts shown, since they may be varied or modified to suit the particular requirement without departing from the invention as expressed in the scope of the appended claims.

What I claim is:

1. In a tube expander in which is included a tubular body having a plurality of longitudinally extended radial slots; an expanding roller for each slot, a spring plate holder for each roller, a bearing member fixedly mounted on each end of the holder, the said bearing members slidably engaging the radial slots, the roller having end journals that engage the bearings, the ends of the said holder having extensions for engaging the inner surface of the tubular body, the said spring plate holder, the bearing and the roller being bodily endwise insertible into and removable from the tubular body, to and from the operative position and adapted, when placed in operative position, to hold the rollers at their innermost position and further adapted, when a tapering mandrel is inserted between the rollers to permit radial adjustment of such rollers.

2. A tube expander comprising a tubular body having one or more longitudinally extended radial slots and a collar at one end, an expanding roller holder located in each slot, each holder consisting of a resilient body, an expanding roller mounted on each holder and normally pulled inwardly, under tension of the said roller holder, the said holder including end bearings for the roller, a flue sheet engaging guard, the said guard being endwise slidable over the tubu-

lar body for engagement with the end collar thereof and means coöperative with one of the roller end bearings and the guard for locking the guard against the aforesaid collar.

3. A tube expander comprising a tubular body having one or more longitudinally extended radial slots; each slot having a narrowed extension at each end, a flue sheet engaging member on the outer end of the said tubular body, an expanding roller holder located in each slot and including end portions for engaging the end extensions of the slots, an expanding roller mounted on the holder and means for normally forcing the holder inwardly under tension, the said holder, the roller and the tension means being insertible and removable as a unit into and from the tubular body, the said holder consisting of end bearing boxes having members for slidably engaging the end extensions of the radial slots and a flat spring member that constitutes the aforesaid tension means having a longitudinal slot through which the inner face of the roller projects, and end portions that embrace and secure the end bearing boxes and end extensions that engage the inner face of the tubular body when the parts are in the operative position.

4. In a tube expander of the character stated, a tubular body having a plurality of radial slots, each including a main portion diagonally disposed relatively to the longitudinal axis of the tubular body and staggeredly disposed opposite end portions projected in the longitudinal plane of the said tubular body, the said end portions including narrowed extensions, and an expanding roller located in the diagonal portion of the slots, each of the said rollers having a center stud journal at each end, a holder for each end of the rollers, the said holders each consisting of a bearing box slidably mounted in the longitudinally extended end portions of the radial slots, and provided with extensions for engaging the narrowed extensions of the radial slots in the tubular holder, and socket bearings for receiving the stud journals on the end of the rollers, a longitudinally slotted spring plate for each roller through which the operating face of their respective rollers project, the said plates having their ends provided with extensions for engaging the tubular body at points beyond the radial slots, the said plates having portions interlockably engaging the bearing boxes so that the tension of the said plates tends to pull the bearing boxes and the rollers mounted thereon inwardly and a tapered mandrel projected in the said tubular body between and engaging the inner adjacent edges of the rollers.

5. In a tube expander having a tubular body formed with longitudinally and radially extended roller receiving slots, the opposite ends of which terminate in narrowed extensions, the said slots being ar-

ranged in a plane diagonal to the longitudinal plane of the roller; of a roller and a holder therefor for each slot comprising end bearing boxes, the said boxes being offset in the longitudinal plane of the holder and slidably engaging the ends of the slots and including extensions for engaging the end extensions of the slot, a

spring plate holder connected with the said boxes and having the ends projected beyond 10 such boxes so that they engage the under face of the tubular body beyond the ends of the slots and a roller having center bearings for engaging sockets in the opposite bearing boxes.

THOMAS J. DIXON.
